UNITED STATES PATENT OFFICE.

JOHN H. MAXHEIMER, OF NEW YORK, N. Y., AND GEORGE C. BERESFORD,
OF SOUND BEACH, CONNECTICUT.

NECKLACE-CLASP.

SPECIFICATION forming part of Letters Patent No. 468,677, dated February 9, 1892.

Application filed March 12, 1891. Serial No. 384,781. (No model.)

To all whom it may concern:

Be it known that we, JOHN H. MAXHEIMER, a resident of New York, in the county and State of New York, and GEORGE C. BERES-
5 FORD, a resident of Sound Beach, in the county of Fairfield and State of Connecticut, both citizens of the United States, have invented a new and useful Necklace-Clasp, of which the following is a specification.

10 Our invention relates to a necklace-clasp in which the catch of the clasp when inserted in the box of the clasp is locked within the box of the clasp by means of a clip.

15 The object of our invention is to provide a necklace-clasp which will be a means of securely fastening a valuable necklace about the neck of a wearer. While the clasp is especially adapted to be used upon necklaces, it is readily available for bracelets or other 20 forms of jewelry. We attain this object by the device illustrated in the accompanying drawings, in which—

Figure 1 is a view of a longitudinal section of the necklace-clasp on the line 1 1 of Fig. 2, showing the box A, spring-catch C, and clip B. Fig. 2 is a view of a longitudinal section of the necklace-clasp on the line 2 2 of Fig. 1, showing the box A, spring-catch C, and clip B. Fig. 3 is a view of a transverse section of 30 the necklace-clasp upon the line 3 3 of Fig. 2, showing the box A, spring-catch C, and clip B. Fig. 4 is a view of a longitudinal section of the necklace-clasp, showing the box A, spring-catch C, and clip B, with projecting end and pin b'', spring b''', and partition a'.

35 Similar letters refer to similar parts throughout.

In the drawings the necklace-clasp is shown in enlarged form. Our necklace-clasp, which 40 is constructed of gold or other suitable material, is provided with a box A. The box A (shown in the drawings) is four-sided; but it may be constructed in cylindrical, oval, or other suitable shape. A spring-catch C fits 45 into one end of the box A, a projection c'' upon the spring-catch engaging in a slot D in the box A and holding the spring-catch in place. Pivoted in the sides of the box A, at b and working in an opening in the box, is a 50 clip B, having a clutch-head b'. The clutch-

head b' is adapted when the clip is pressed inward to pass through the spring-catch C, thereby preventing the spring-catch C from being drawn outward, Figs. 1, 2, and 3.

To obviate any tendency of the clutch-head 55 b' of the clip B to work out of position when locking the spring-catch C, a projecting end, with pin b'', is constructed upon the clip B, the pin b'' being inserted into a spring b''' in contact with a partition a' in the box A, 60 Fig. 4.

The operation of our necklace-clasp is as follows: One end of the necklace or bracelet is attached to the spring-catch C by a lug c' or other suitable fastening, and the other end 65 of the necklace or bracelet is attached to the box A by a similar lug or fastening a. The spring-catch C is compressed and inserted into the box A. The clip B, having been drawn outward to allow of the insertion of the spring- 70 catch C into the box A, is again pressed inward and through the spring-catch, the clutch-head b' locking the spring-catch in the box A, Figs. 1, 2, and 3. When the necklace-clasp is constructed with a clip B, having a projecting end with pin b'', in connection with spring b''' and partition a', the pressure of the spring b''' from the direction of the front of the box A upon the projecting end and pin b'' holds 75 the clip B in locking position through the spring-catch C. If the clip B be drawn outward, the spring b''' is compressed and causes the clip when the outdrawing force is relieved to spring back in locking position through the spring-catch C, Fig. 4. This construction is especially well adapted to prevent 80 the outdrawing of the clip B should it become entangled with laces or other fine fabrics. 85

Having fully described our invention, what we claim, and desire to protect by Letters Patent, is—

1. The combination, in a necklace-clasp, of a box, a spring-catch adapted to be inserted in said box, and a clip to lock said spring-catch in said box, the clip when in locking 95 position passing through the spring-catch, substantially as set forth.

2. The combination, in a necklace-clasp, of a box, a spring-catch adapted to be inserted in said box, and a clip to lock said spring- 100

catch in said box, the clip being held in locking position in the spring-catch by the pressure from the direction of the front of the box of a spring contained within the box, substantially as set forth.

5 3. The combination, in a necklace-clasp, of a box, a spring-catch adapted to be inserted in said box, and a clip to lock said spring-catch in said box, the clip having on its piv-

oted end a projection and pin, said pin being inserted in a spiral spring having its base in contact with a partition in said box, substantially as set forth.

JOHN H. MAXHEIMER.

GEORGE C. BERESFORD.
